BUCKET

William J. Rathaus, 296 Bowles Ave., Fenton, Mo.

Filed Mar. 11, 1963, Ser. No. 73,927

Term of patent 14 years

(Cl. D58—17)

FIG. 1

FIG. 2

FIG. 3

FIG. 5

FIG. 4

FIG. 6

FIG. 1 is a top plan view of the bucket showing my new design;

FIG. 2 is a front elevational view thereof;

FIG. 3 is a side elevational view thereof, the side opposite being a mirror image of the side depicted,

FIG. 4 is a cross-sectional view taken along the line 4-4 of FIG. 2;

FIG. 5 is a rear elevational view thereof; and

FIG. 6 is a bottom plan view thereof.

I claim:

The ornamental design for a bucket, as shown and described.
